(57) **CLAIM**

The ornamental design for an electronic connection hub, as shown and described.

DESCRIPTION

FIG. 1 is a top perspective view of an embodiment of the electronic connection hub of the claimed invention.

FIG. 2 is a bottom perspective view of the electronic connection hub of FIG. 1.

FIG. 3 is a front side elevation view of the electronic connection hub of FIG. 1.

FIG. 4 is a back side elevation view of the electronic connection hub of FIG. 1.

FIG. 5 is a right side elevation view of the electronic connection hub of FIG. 1.

FIG. 6 is a left side elevation view of the electronic connection hub of FIG. 1.

FIG. 7 is a top plan view of the electronic connection hub of FIG. 1.

FIG. 8 is a bottom plan view of the electronic connection hub of FIG. 1; and,

FIG. 9 is a top plan view of an alternative embodiment of the electronic connection hub of FIG. 1, showing light emitting from a perimeter portion of the electronic connection hub. The intersecting dot lines shown in FIG. 9 represent light rays that are emitted from interior decorative lighting sources within the various embodiments of the electronic connection hub.

The broken lines shown in the drawings illustrate portions of the electronic connection hub, which form no part of the claimed design.
